Inventor

L. N. Gillis

UNITED STATES PATENT OFFICE.

LYLE N. GILLIS, OF ROSE CREST, VIRGINIA, ASSIGNOR, BY DIRECT AND MESNE ASSIGNMENTS, OF ONE-HALF TO THE FLOOROLA CORPORATION, OF BALTIMORE, MARYLAND, A CORPORATION OF DELAWARE, AND ONE-HALF TO ERNEST J. NEWCOMER, OF BALTIMORE, MARYLAND.

BRUSH HOLDER FOR FLOOR POLISHERS.

Application filed February 12, 1924. Serial No. 692,299.

This invention relates to floor polishing and scrubbing machines such as are shown in my copending applications for patents No. 661,424 filed September 7, 1923; No. 5 692,295, filed February 12, 1924, and No. 692,296 filed February 12, 1924; and has special reference to brush holders therefor.

The principal objects of the invention are to provide new and improved brush holders 10 for the purpose wherein provision is made for quickly and easily changing brushes, polishers and the like, it being understood that the word "brush" as herein used is intended to cover brushes properly so 15 called, wax distributors, polishing pads or blocks, sanding devices and all other attachment of like general character.

With the above and other objects in view as will be hereinafter apparent, the invention 20 consists in general of certain novel details of construction and combinations of parts hereinafter fully described, illustrated in the accompanying drawings and specifically claimed.

25 In the accompanying drawings like characters of reference indicate like parts in the several views, and:

Figure 1 is a bottom plan view of the holder.

30 Figure 2 is a section on the line 2-2 of Figure 1.

Figure 3 is an enlarged detail section in the line 9-9 of Figure 1.

In the form herein described the body of 35 the holder comprises an elongated plate 10 having rounded corners.

In the form shown in Figures 1 to 3 there is provided at one end a downwardly extending lug 18 having an inwardly extending portion 19, thus forming an L-shaped 40 structure. At the other end there is secured, by welding, or the like, a downwardly extending case 20 wherein is slidably mounted a bolt 21 having a bevel face 22.

45 This bolt is normally pressed in the direction of the lug 18 by a spring 23 and on the outer end of the bolt is secured a thumb piece 24 which is fixed to the outer end of the bolt and bent over the lower end of the 50 case to act as a guide and prevent rotation of the bolt 21.

In this form the lug end of the brush is first inserted and the other end simply slid

in past the bolt, the bevel bolt permitting this. To withdraw the brushes from this 55 form the thumb piece is drawn back to allow the latch end of the brush to drop.

There has thus been provided a simple and efficient device of the kind described and for the purpose specified. 60

It is obvious that minor changes may be made in the form and construction of the invention without departing from the material spirit thereof. It is not, therefore, desired to confine the invention to the exact 65 form herein shown and described, but it is desired to include all such as properly come within the scope claimed.

Having thus described the invention, 70 what is claimed as new, is:

1. A rotatable brush holder for floor polishers consisting of a plate having a depending lug at one end provided with an inturned extremity, a latch housing depending from the plate at the other end wherein is mounted a latch having a bevel ended spring pressed bolt projecting toward the lug, and a thumb piece for drawing said latch backward against the spring. 75

2. A rotatable brush holder for floor polishers consisting of a plate having a depending lug at one end provided with an inturned extremity, a latch housing depending from the plate at the other end wherein is mounted a latch having a bevel ended spring pressed bolt projecting toward the lug, a thumb piece for drawing said latch backward against the spring, and side flanges depending from the plate to engage the sides of the brush back and prevent lateral movement of said brush with 80 respect to the plate. 90

3. A brush holder including a backing plate having a depending lug, a latch housing depending from said plate, and a spring pressed latch carried by said housing in opposition to said lug. 95

4. A brush holder including a backing plate having a depending lug, a latch housing depending from said plate, a spring pressed latch projecting toward said lug in opposition to said lug, and a thumb piece for moving said latch back against the tension of the spring. 100

5. A brush-holder including a backing-plate, means mounted thereon for engaging 105

an end of a brush, a latch housing carried by said plate at the opposite side thereof, a latch slidably mounted in the housing for engaging the brush, and a thumb-plate 5 connected with the latch and bent over the end of the housing for moving said latch and for preventing the turning thereof.

6. A brush-holder including a backing-plate, a lug mounted thereon for engaging 10 an end of a brush, a latch housing depending from the opposite end of the plate, a

spring-pressed latch slidably mounted in the housing for engaging and holding the brush, the back end of said latch projecting through the back of the housing, and a 15 thumb-plate fixed on said back end and bent over the end of the housing for sliding said latch and for preventing turning movement thereof.

In testimony whereof I affix my signature.

LYLE N. GILLIS.
